(57) **CLAIM**

The ornamental design for a safety razor chassis, as shown and described.

DESCRIPTION

FIG. 1 is a front perspective view of a safety razor chassis; FIG. 2 is a rear perspective view thereof; FIG. 3 is a top view thereof; FIG. 4 is a bottom view thereof; FIG. 5 is a left side elevational view thereof, the right side being a mirror image; FIG. 6 is a front elevational view thereof; FIG. 7 is a rear elevational view thereof; FIG. 8 is a front elevational view of the safety razor chassis connected to a pair of razor cartridges and a handle showing my new design; and, FIG. 9 is a front perspective view of the safety razor chassis connected to the pair of razor cartridges and the handle. The pair of razor cartridges and the handle illustrate the environment of the safety razor chassis and form no part of the claimed design.
